FEEDING MECHANISM FOR TINNING-MACHINES.

1,064,781.

Specification of Letters Patent. Patented June 17, 1913.

Application filed August 17, 1910. Serial No. 577,717.

To all whom it may concern:

Be it known that I, RALPH S. SCHRUMM, a resident of Tarentum, in the county of Allegheny and State of Pennsylvania, have invented certain new and useful Improvements in Feeding Mechanism for Tinning-Machines, of which the following is a specification.

The prime object of my invention is to provide a new and improved automatic plate or sheet feeding or delivering mechanism particularly designed for conveying plates or sheets one by one from a pile to a machine, such for example as, a tinning machine.

In the accompanying drawings, which illustrate an application of my invention Figure 1, is a central longitudinal sectional view of an apparatus embodying my invention, the section being taken on line 1—1 of Fig. 2; Fig. 2, a plan; Fig. 3, a front elevational view with a portion of movable platform broken away; Fig. 4, a longitudinal section taken on line IV—IV of Fig. 3; 25 particularly showing the fork operating mechanism; Fig. 5, a side view of the movable carrier; and Fig. 6, a rear elevation of the carrier.

Referring to the drawings, 2 designates a liquid containing tank or feed box designed to hold in addition to the liquid, a pile of plates 3. As illustrated, tank 2 is mounted on a car 4 which is designed to be run into a convenient position for the plates to be reached by the automatic feed mechanism. The plates are preferably supported by an adjustable false bottom or rack 5 disposed in an inclined position by means of a series of ledges as 6 formed in a wall of the tank. By 40 the employment of the adjustable rack 5 and its supports, I am enabled to raise or lower the rack to properly position plates of different sizes.

7 designates a flux-box or a portion of the tinning machine into which the plates are to be delivered. As shown, box 7 is provided with guide-ways 8 and 9. Located over the tank is a pivoted frame comprising two side members 10 hinged to a support or a wall as indicated at 11 by means of clamps 12. Members 10 at their inner ends are enlarged as shown at 13 and are connected by shafts 14, 15, 16, and 17. Fixedly secured to the

respective enlarged ends of members 10 and depending therefrom I provide slotted 5: guides 18. The forward ends of the members 10 in addition to supporting the shafts 14, 15, 16 and 17 support a rod 19 having its bearings in bent arms 20, the latter being pivotally connected with the enlarged 60 ends 13.

21 designates guide arms for the moving plates and 22 rollers on rod 19.

Mounted on shaft 14 I provide two rollers 23 between which and the rollers 22 the 65 plates are adapted to pass on their travel to the tinning machine. Shaft 14 is also provided with three toothed pulley wheels 24 and with a wheel 25, the latter being designed to receive a driving chain 26 extending from a driving wheel 27 mounted on and adapted to rotate with a main drive shaft 28. Main shaft 28 is driven by any suitable means, as illustrated it is provided with a belt pulley 29 designed to receive a belt, not 70 shown. Shaft 15 carries three loose guide pulleys 30 and shaft 16 a corresponding number of pulley wheels 31. Shaft 16 is located in the slotted guides 18, directly below and in line with shaft 14 with the wheels 31 80 thereon in line with wheels 24, and is designed to move vertically therein as herein-after described. Cross-rod or shaft 17 is designed to support the upper end of a movable skeleton platform 32.

85 Supported by members 10 and mounted on grooved wheels 33 I provide a movable carrier or carriage comprising two side parts with each part comprising a casting having a member 33^a and two angular depending 90 members 34 and 35 connected by shafts as hereinafter described. In addition to the parts mentioned, the carrier comprises two depending arms each comprising integral members 36 and 37, the arms being connected with the lower ends of members 35 by a shaft 38 extending across and connecting the respective side parts of the carriage. Extending from one side part of the carriage to the other in addition to shaft 38, I provide shafts 39, 40, 41, 42, and 43 connecting said side parts. The wheels 33 are mounted on shaft 39 and said shaft 39 is provided with two gear-wheels 43^a, respectively adapted to mesh with and drive gear-wheels 105 44 carried on the ends of shaft 40; three

toothed pulley wheels 44, over which three plate conveyer chains 45 extending from shaft 14 pass, and with two nicked rollers or disks 46. Shaft 40 also has mounted thereon two rollers 47 between which and the rollers 46 the plates are passed, and a toothed wheel 48. Shaft 41 is driven by means of a chain 49 extending from wheel 48 over a wheel 50 mounted on shaft 41.

10 Mounted on and movable with shaft 41 is a cam 51 the latter being designed to engage the free end of a pivoted rod 52. Rod 52 is carried by shaft 43 and has a lower portion 53 adapted to make contact with the outer plate of the pile of plates 3. Shaft 38 located below and slightly in advance of shaft 41 is connected with the latter shaft and driven by a chain 54 leading from a wheel 55 on shaft 41 to a wheel 55^a on shaft 38.

15 56 designate rotative and bodily movable friction rolls adapted to successively engage at predetermined intervals successive outer plates of the pile of plates to be operated on.

20 These rolls are carried on shaft 38 and move forward with the forward movement of the carriage. Located on shaft 42, which is located below and slightly to the rear of shaft 38, are two plate engaging friction rolls 57. Shaft 42 together with the rolls 57 are driven by means of a chain 58 extending over wheel 59 on shaft 38 and a wheel 60 secured to shaft 42. Rolls 57 like rolls 56 are arranged to be moved into contact with the outer plate of the pile of plates and away from said pile at predetermined intervals and the means as illustrated for bodily moving said rolls, comprise the cam 51 and the pivoted rod 52.

25 30 The lower portion 53 of rod 52 is designed to fall into contact with the succeeding outer plate as soon as the outer plate of the pile is moved by the friction rolls, above the portion 53, but the cam acting against the free end of rod 52 moves said friction rolls away from the pile of plates and prevents the rolls acting to force the succeeding plate upwardly until the plate previously moved has reached the conveyer chains 45. It will be

35 40 45 noted that as the pile of plates diminishes, the carriage is moved forward and in order to take up the slack in the conveyer chains 45 the shaft 16 is moved downwardly in its slotted guides. Suitable guide pieces 61, 62 and 63 are provided on the carriage designed to guide the plates between the rollers 46 and 47 on shafts 39 and 40 and onto the conveyer chains 45.

45 50 55 The movable platform 32 connected with cross-rod 17 at one end extends downwardly in an inclined direction to near the flux-box and is provided with downwardly extending bent arms 64 rigidly connected with the platform having their lower ends connected by a pin 65. Pin 65 and the arms

are raised by means of a cam 66 carried on main shaft 28, and the platforms being rigidly connected with arms 64 is likewise raised. The purpose of raising arms 64 is to bring the platform 32 into register with the upper guide way of the flux-box.

67 designate stops carried on the platform to stop or retard the movement of the plates down said platform so that they may be engaged by a movable fork 68. The fork 68 has two plate engaging jaws 69 and said fork is moved forward toward the machine by mechanism comprising an upwardly extending arm 70 pivoted near its lower end to a frame 71 by means of a pin 72. Arm 70 is provided with an extension 73 bent at an angle with the arm proper and mounted on portion 73 I provide an adjustable weight 74. Mounted to slide on frame 71 are two members 75 and these members are connected by cross-pins 76 and 77. Pin 76 projects through an opening 78 in arm 70 and pin 77 is designed to make contact with and be moved forward by a double eared cam 79 rotatable with the main drive shaft 28. The ears of cam 79 are of slightly different size, thus as shown ear *a* is of slightly larger size than ear *b*; the purpose of making the ears of different sizes is to vary the length of the forward movement of the fork when it is employed in connection with a flux-box having a double pass as shown by the drawings. Joined to the upper end of arm 70 and extending from said arm at right angles thereto is a second arm or member 80 having a bent portion 81. The upper end of the fork 68 is secured to the end of portion 81 by means of an adjustable clamp 82. On the inner end of arm 80 I provide a gear-wheel 83 adapted to mesh with a rack 84 carried on the upper end of a rod 85. Rod 85 at its lower end is pivoted to the frame 71. This mechanism just described provides for the forward movements of the fork carrying a plate grasped on the inclined platform. The backward movement of arm 70 is effected by means of the weight 74 and the backward movement of the fork is effected by the movement of arm 70 cooperating with the rack 84.

100 105 110 115 120 125 130 In operation the sheets or plates are passed upwardly from the pile singly and successively to and between the rollers 46 and 47 by the friction wheels 56 and 57 acting at predetermined intervals upon the outer sheet or plate of the pile. After a sheet or plate passes rollers 46 and 47 it is conveyed by means of conveyer chains 45 between rollers 22 and 23 onto the inclined movable platform 32 and the plate held in position on said platform by means of the stops 67 until it is grasped by the movable fork 68 actuated by the mechanism described. Plates are passed alternately through the guideways in the flux-box by raising and

lowering the platform 32 as above described, and by the forward movement of the fork 68.

As above stated, the arm 70 is provided with a slot 78 through which a pin 76, carried by the sliding members 75 projects, and the forward movement of said members 75 as well as the pin 76 and arm 70 are effected by means of the cam 79 acting against the pin 77. It will be noted that the construction is such that a very slight forward movement of the pin 76 acting in slot 78 of arm 70 will cause a considerable movement of the outer end of the arm 70, as particularly shown by Fig. 1.

What I claim is:

1. The combination with a tinning pot, of means for automatically moving plates one by one from a pile to the pot comprising a 20 rotative friction roller, means for moving the roller away from the pile and causing it to engage a succeeding plate at a predetermined interval, an inclined movable platform, means for raising and lowering the 25 platform, a plate engaging member operable to engage a plate on the platform and pass it forward to the tinning pot, and means operable to move the last mentioned member toward and away from the tinning pot.

2. The combination with a tinning pot, of means for automatically moving plates one by one from a pile to the pot comprising a rotative friction roller, means for moving the roller away from the pile and causing it to engage a succeeding plate at a predetermined interval, an inclined movable platform, means for raising and lowering the platform, plate conveying means between the friction roller and the platform, a plate 40 engaging member operable to engage a plate on the platform and pass it forward to the tinning pot, and means operable to move the last mentioned member toward and away from the tinning pot.

3. In a tinning machine feeding apparatus, means for automatically moving plates one by one from a pile comprising a movable carrier, an inclined track on which the carrier moves, a rotative friction roller 50 movable with the carrier, and means movable with the carrier for moving the roller away from the pile and causing it to engage a succeeding plate at a predetermined interval.

4. The combination with a tinning pot, of means for automatically moving plates one by one from a pile to the pot comprising a rotative friction roller, means for moving the roller away from the pile and causing it to engage a succeeding plate at a predetermined interval including a cam and means coacting with the cam, an inclined movable platform, means for raising and lowering the platform, plate conveying 60 means between the friction roller and the

platform, a plate engaging member operable to engage a plate on the platform and pass it forward to the tinning pot, and means operable to move the last mentioned member toward and away from the tinning 70 pot.

5. In a tinning machine feeding apparatus, means for automatically moving plates one by one from a pile comprising a 75 movable carrier, a rotative and bodily movable shaft supported by the carrier, a friction roller on the shaft, a second shaft supported by the carrier, a cam on the second shaft, and means coacting with the cam for moving the roller away from the pile and causing it to engage a succeeding plate at a predetermined interval.

6. In a tinning machine feeding apparatus, means for automatically moving plates one by one from a pile comprising a 85 movable carrier, a support therefor, a rotative friction roller, a set of rolls between which the plate is passed, a movable platform, means for raising and lowering the platform, means for conveying the plate 90 from the last mentioned rolls to the platform, means for moving the friction roller away from the pile and causing it to engage a succeeding plate at a predetermined interval, and means for engaging the plate on 95 the platform and passing it forward.

7. In a tinning machine feeding apparatus, means for automatically moving plates one by one from a pile comprising a movable carrier, a support therefor, a rotative friction roller, a set of rolls between which the plate is passed, an inclined platform, and plate conveying means between the inclined 100 platform and the set of rolls.

8. In a tinning machine feeding apparatus, means for automatically moving plates one by one from a pile comprising two rotative friction rollers arranged one above the other, rotative and bodily movable shafts on which the rollers are mounted, a movable 105 carrier, a support therefor, said shafts being supported by the movable carrier.

9. In a feed mechanism for delivering plates one by one from a pile, the combination with a carrier, of a positively driven 115 rotative friction roller supported from the carrier, means for moving the roller at predetermined intervals into contact with the outer plate of the pile, rolls between which the plate is passed, a movable platform, and conveying means between the rolls and platform.

10. In a tinning machine feeding apparatus, means for automatically moving plates one by one from a pile comprising a 125 rotative friction roll, a rotatable and bodily movable shaft on which the friction roll is mounted, a set of rolls between which the plate is passed, a movable platform, means between the platform and the set of rolls 130

for conveying the plate from the rolls to the platform, and means for engaging the plate while on the platform and passing it forward.

5 11. In a tinning machine feeding apparatus, means for automatically moving a plate comprising a friction roll, a set of rolls between which the plate travels, an inclined platform, means for conveying the 10 plate from the set of rolls to the platform, and means for engaging the plate while on the platform and passing it forward.

12. In a tinning machine feeding apparatus, a movable carrier, a set of rolls on 15 the carrier, and means operable to move plates one by one from a pile of plates to the rolls.

13. In a tinning machine feeding apparatus, a movable carrier, a set of rolls on 20 the carrier, means operable to move plates one by one from a pile of plates to the rolls, a plate conveying chain, and means coacting with the chain for preventing slack occurring in the chain.

25 14. In a tinning machine feeding apparatus, a movable carrier, a plate conveying chain movable with the carrier, means operable to move a plate from a pile of plates to the conveying chain, and means coacting 30 with the conveying chain for preventing slack occurring in the chain.

15. In a tinning machine feeding apparatus, a movable carrier, an inclined support therefor, a plate conveying chain movable with the carrier, means operable to 35 move a plate from a pile of plates to the

conveying chain, and means coacting with the conveying chain for preventing slack occurring in the chain.

16. The combination with a tinning pot, 40 an inclined movable platform, means including a cam for raising the platform, and a movable plate engaging member for pushing the plate through the tinning pot.

17. The combination with a tinning pot, 45 an inclined pivoted platform having a rigid depending arm, means including a cam co-operating with the arm for raising the platform, and a movable plate engaging member for pushing the plate through the tinning 50 pot.

18. The combination with a tinning pot, an inclined movable platform having connected depending arms, means including a cam co-operating with the arms for raising 55 the platform, and a movable plate engaging member for pushing the plate through the tinning pot.

19. The combination with a tinning pot, 60 an inclined movable platform having a rigid depending arm, means including a cam co-operating with the arm for raising the platform, means operable to move plates one by one from a pile of plates to the platform, and a movable plate engaging member for 65 pushing the plate through the tinning pot.

In testimony whereof I affix my signature in presence of two witnesses.

RALPH S. SCHRUMN.
